Primary Examiner—Marcus A. Jackson*(74) Attorney, Agent, or Firm*—Gregory J. Adams(57) **CLAIM**

We claim the ornamental design for a flashlight, as shown and described.

DESCRIPTION

FIG. 1 is a top right perspective view of the flashlight of the design.

FIG. 2 is a bottom right perspective view of the flashlight of the design.

FIG. 3 is a top view of the flashlight of the design.

FIG. 4 is a bottom view of the flashlight of the design.

FIG. 5 is a right side view of the flashlight of the design. A left side view is a mirror image of the left side view.

FIG. 6 is a front view of the flashlight of the design.

FIG. 7 is a rear view of the flashlight of the design.

FIG. 8 is another top right perspective view of the flashlight of the design with a lanyard.

FIG. 9 is another bottom right perspective view of the flashlight of the design.

FIG. 10 is another top view of the flashlight of the design.

FIG. 11 is another bottom view of the flashlight of the design.

FIG. 12 is another right side view of the flashlight of the design. A left side view is a mirror image of the left side view.

FIG. 13 is another front view of the flashlight of the design; and,

FIG. 14 is another rear view of the flashlight of the design.

Any broken line(s) shown are for illustrative purposes only and form no part of the claimed design.
